G. E. PRENTICE,
CORD EYE FOR CORD BACK SUSPENDERS.
APPLICATION FILED DEC. 9, 1913.

1,110,145.

UNITED STATES PATENT OFFICE.

GEORGE E. PRENTICE, OF NEW BRITAIN, CONNECTICUT.

CORD-EYE FOR CORD-BACK SUSPENDERS.

1,110,145.

Specification of Letters Patent.

Patented Sept. 8, 1914.

Application filed December 9, 1913. Serial No. 805,627.

To all whom it may concern:

Be it known that I, GEORGE E. PRENTICE, a citizen of the United States, and resident of New Britain, in the county of Hartford and State of Connecticut, have invented new and useful Improvements in Cord-Eyes for Cord-Back Suspenders, of which the following is a specification.

This invention relates to cord eyes for 10 suspenders or other garment supporters in which cords are used, and its object is to provide a cord eye through which the cord will easily slip, having the novel and improved features of construction hereinafter 15 described and particularly pointed out in the claims.

The invention comprises certain improvements upon and modifications of the cord eye set forth in an application for Letters 20 Patent of the United States filed by me May 21, 1913, Serial Number 769,056, allowed November 13, 1913.

In the accompanying drawings which illustrate certain embodiments of the invention applied to suspenders or braces,—Figure 1 is a front view of a pair of suspenders containing the invention; Fig. 2 is an enlarged side view of one of the cord eyes and its supporting bar; Fig. 3 is a vertical longitudinal section of the cord eye and supporting bar of Fig. 2; Fig. 4 is an end view of said cord eye and bar; Fig. 5 is a vertical cross section of said cord eye and bar, showing the manner of attachment of the shoulder strap; Fig. 6 is a plan view of a metal blank for making the cord eye according to Figs. 2 to 5; Fig. 7 is a vertical longitudinal section of a modified form of cord eye; and Fig. 7^a is a plan view of a metal blank for 30 making the same; Fig. 8 is a plan view of the metal blank for making the said supporting bar; and Fig. 9 is a plan view of the metal blank for making the rocker shown in said cord eyes.

45 The suspender or brace has the ordinary shoulder straps A, A, preferably of elastic webbing or the like, and cords B, B, at the front ends of the shoulder straps, provided with loops 15 to be buttoned to the front 50 of the garment. The length of the loops at the front ends of the shoulder straps is adjusted by the usual buckles 23. The rear

ends of the shoulder straps are provided with cord eyes through which passes the cord C.

55 D is a band, preferably of elastic webbing or the like, having three cord eyes at the top and one cord eye at the bottom through which the cord C passes, as shown. The lower ends of cord C are formed into loops 60 15 for attachment to the rear of the garment.

The cord eyes E of the preferred construction, are each formed from a blank of a single piece of sheet metal shaped as shown 65 in Fig. 6. When the blank is properly folded, it forms a housing, of which 1, 1, are the side walls rising from opposite edges of the end wall 2. The arms 3, 3, are bent inward at the top of the side walls, 70 and then extend upward side by side and constitute a shank to connect the cord eye to the supporting bar.

In the preferred form illustrated in Figs. 2 to 6, the side wings 4 and 4^a, extending 75 from the other two edges of the end wall 2, are folded inward toward each other, forming with the end wall 2 a socket chamber, to conceal and protect the end of the shank of the rocker hereinafter described. The 80 wing 4 is made with a socket aperture 5. The middle of wall 2 is pressed outwardly to form a little bowl 6, thus enlarging the socket chamber at that point, to receive the shank of the rocker.

85 Within the housing is the rocker 7, formed from a blank of sheet metal shaped as shown in Fig. 9. The rocker 7 has a smooth convex top surface formed from the middle part of the blank, while the ends are 90 bent back underneath the convex top to provide a shank formed of the two tenons 8, extending downwardly from the under side of the rocker. Said shank loosely fits the socket aperture 5 and extends into the 95 socket chamber between the infolded wings 4, 4^a, and the end wall 2. Thus all pivotal connections are wholly inclosed, and the housing presents a smooth and unbroken exterior, which protects the clothes of the 100 wearer from damage from projecting or working parts. The ends of the tenons 8 are preferably bent over in opposite directions as best shown in Figs. 3 and 7, to form

a head on the shank for preventing the shank from being dislodged from the socket aperture.

In the modification shown in Figs. 7 and 5 7^a, the connecting end wall 2 is pressed upwardly or inwardly instead of outwardly, and is made with a socket aperture 5^a for the shank of the rocker. And the socket chamber for inclosing and protecting the shank of the rocker is formed by bending the wings 4^b, 4^b, downward instead of upward, until their edges meet underneath the shank of the rocker, thus closing the socket chamber.

15 It will be seen that in either form of the cord eye as shown in Figs. 2 to 6, or in Figs. 7 and 7^a, the top wall of the socket chamber forms a platform on which the rocker rests, and the bottom wall of the socket chamber 20 forms an outer inclosing wall which covers and protects the socket aperture and the shank of the rocker. In the form of the invention shown in Figs. 2 to 6, the infolded wings 4 and 4^a constitute such platform, the 25 socket aperture being formed through the wing 4, as shown at 5, while the end wall 2 connecting the lower ends of the side walls 1 constitutes the outer inclosing wall of the socket chamber to cover and protect the ends 30 of the rocker shank 8. In the form shown in Figs. 7 and 7^a, the end wall 2 of the blank constitutes the platform for supporting the rocker, the socket aperture 5^a being formed through said platform, while the infolded 35 wings 4^b, 4^b, constitute the outer inclosing wall to cover and protect the ends of the rocker shank 8.

The cord C passes through the housing in engagement with the convex surface of the 40 rocker, which tilts in response to the movements of the cord.

The supporting bar to which the cord eye E is secured, is made from a sheet metal blank shaped as shown in Fig. 8, and provided with a slot 9. The arms 3 of the 45 cord eye E are passed through a slit in the fold of a loop at the end of the strap A. The tip ends of arms 3 are bent outwardly as shown at 10 to form a head. The blank 50 for the supporting bar is then folded along its center line, the fold being preferably in the shape of a little tube as shown, to stiffen the bar, and the ends 10 of arms 3 are inserted into the slot 9. Then the two sides 55 or leaves 11 and 11 are bent downwardly at each side of the arms 3, with the head 10 anchored in slot 9 and securely locking the cord eye to the bar thus formed. The loop of strap A is then fastened by stitches above 60 the bar in the manner shown in Fig. 5. By this construction the fabric wholly incloses the supporting bar and the devices connecting the cord eye to the bar.

The cord eyes E above described may be 65 used at any point where the cord is to be

connected to the straps. In Fig. 1 of the drawings they are shown at the rear ends of the shoulder straps A, and at each end of the band D, while simple tubular eyes or loops 13 are used at the sides of the band D, 70 and at the front ends of the shoulder straps.

I claim:—

1. A cord eye comprising a housing having side walls and a socket aperture at its lower end, and a rocker in said housing, said 75 rocker having a cord support at its upper end and a shank on its under side loosely engaging said socket aperture.

2. A cord eye comprising a housing having side walls, a platform at its lower end 80 provided with a socket aperture, a rocker in said housing having a cord support at its upper end and a shank on its under side loosely engaging said socket aperture, and said housing having an outer inclosing wall 85 covering and protecting said socket aperture and the end of the shank on the rocker.

3. A cord eye comprising a housing having side walls, an end wall from the two opposite edges of which said side walls rise, 90 and two wings extending from the other two edges of said end wall and folded toward each other to form with the end wall a socket chamber, a socket aperture through the top of said socket chamber, and a cord 95 supporting rocker having a shank on its under side loosely fitting said socket aperture and extending therethrough into the socket chamber.

4. A cord eye comprising a housing having side walls, an end wall from the two opposite edges of which said side walls rise, and two wings extending from the other two edges of said end wall and folded toward each other to form with the end wall a 100 socket chamber, a socket aperture through the top of said socket chamber, and a cord supporting rocker having a shank on its under side loosely fitting said socket aperture, and extending therethrough into the 105 socket chamber, the end of said shank being formed with a head within said socket chamber to prevent the shank from being dislodged from said socket aperture.

5. A cord eye comprising a housing made 115 of a single piece of sheet metal forming side walls, an end wall from the two opposite edges of which said side walls rise, and two wings extending from the other two edges of said end wall and bent upwardly and inwardly into the housing and made with a socket aperture, said wings and end wall constituting a socket chamber, and a rocker made of a single piece of sheet metal the ends of which are bent toward each other 120 and downwardly to form a shank on the under side of the rocker, said shank extending through said socket aperture into the socket chamber.

6. A cord eye comprising a housing made 130

of a single piece of sheet metal forming side walls, an end wall from the two opposite edges of which said side walls rise, and two wings extending from the other two edges of said end wall and bent upwardly and inwardly into the housing and made with a socket aperture, said wings and end wall constituting a socket chamber, and a rocker made of a single piece of sheet metal, 5 the ends of which are bent toward each other and downwardly to form a shank on the un-

der side of the rocker, said shank extending through said socket aperture into the socket chamber, and the center of said end wall being pressed outwardly to form a bowl-like cavity to receive the shank of the rocker. 15

Signed by me at Boston, Massachusetts, this 25th day of November, 1913.

GEORGE E. PRENTICE.
